UNITED STATES PATENT OFFICE.

WILLIAM J. F. MAIDHOF, OF NEW YORK, N. Y.

METHOD OF WATERMARKING PAPER.

1,094,799.

Specification of Letters Patent. Patented Apr. 28, 1914.

Application filed October 6, 1909. Serial No. 521,353.

To all whom it may concern:

Be it known that I, WILLIAM J. F. MAIDHOF, a citizen of the United States, and resident of the borough of Bronx, in the city and 5 State of New York, have invented a new and useful Method of Watermarking Paper, of which the following is a specification.

This invention relates to an improved method of water-marking paper, with the 10 object in view of providing a method by which paper may be water-marked at any time, even after it has been manufactured, and without the necessity of any preparatory treatment; and in carrying out which 15 method any ordinary printing or embossing form may be used.

It has heretofore been customary to watermark paper during the process of its manufacture, thus requiring a very large amount 20 of paper to be stamped with a given mark in order to prevent the cost of water-marking rendering the price of the paper commercially prohibitive.

My method is especially adapted for marking 25 small lots of paper because it may be carried out in connection with finished paper.

A practical form of means for carrying out my method is represented in the accompanying drawings, in which,

Figure 1 represents a detail vertical section through the cylinders of a rotary cylinder printing or embossing machine arranged to carry out my method: Fig. 2 35 represents a detail view of the form or plate and the character thereon, the character being covered by a roughened sheet partially broken away: Fig. 3 represents a view similar to Fig. 2, except that the roughened 40 sheet takes the form of the character, and Fig. 4 represents a detail view of a piece of paper with the character water-marked thereon.

The form cylinder is denoted by 1 and the 45 impression cylinder by 2. The former is provided with an ordinary form or plate 3 secured thereon by clamps 4 and screws 5. The impression cylinder is provided, in the usual manner, with rollers 6 and guides 7 50 for carrying a tympan 8. The web or sheet to be water-marked is indicated by 9. The form 3 is provided with a raised character

10 on its face, in the present instance, the letter A. On the face of the form or plate, I secure, in any desired manner, such as by 55 an adhesive, a roughened sheet 11, preferably a textile fabric such as linen. This sheet may be of any convenient shape, and of sufficient size to cover the character which it is desired to water-mark on the paper, as 60 indicated in Fig. 2, or it may conform to the shape of the character as indicated in Fig. 3.

In operation, after the roughened sheet is secured in place, the web or sheet to be marked is subjected to the action of the 65 cylinders. As a result, the character on the form or plate 3 will be embossed on the web or sheet 9, in exact simulation of a watermark: the roughened sheet causing the character to have a dull appearance as of a 70 quantity of intersecting lines or adjacent marks.

It will be seen that this method is comparatively cheap and rapid and extremely desirable in that it permits the commercial 75 water-marking of small lots of paper after the latter is manufactured.

It is to be understood that various changes may be made in the form, construction and arrangement of the means for carrying out 80 my method; hence I do not wish to limit myself strictly to the mechanism herein shown and described, but

What I claim is:

1. The method of water-marking paper 85 consisting in subjecting the paper to the action of a printing or embossing machine while a roughened sheet is interposed between the printing face of the form and the paper to be marked.

2. The method of water-marking paper 90 consisting in subjecting the paper to the action of a printing or embossing machine while a sheet of textile fabric is interposed between the printing face of the form and the paper to be marked.

In testimony, that I claim the foregoing as my invention, I have signed my name in presence of two witnesses, this fourth day of October, 1909.

WILLIAM J. F. MAIDHOF.
